UNITED STATES PATENT OFFICE.

GEORGE ABNER STILES, OF WEST GARDNER, ASSIGNOR TO WARREN HILL,
OF BOSTON, MASSACHUSETTS.

SYRINGE.

SPECIFICATION forming part of Letters Patent No. 292,381, dated January 22, 1884.

Application filed September 13, 1883. (Model.)

To all whom it may concern:

Be it known that I, GEORGE ABNER STILES, a citizen of the United States, residing at West Gardner, in the county of Worcester and State 5 of Massachusetts, have invented an Improved Attachment for Syringes, of which the following is a specification.

My invention relates to syringes which are used in cleansing the vagina and other channels of the human body; and the object of my invention is the provision of an attachment for such syringes by means of which the said channels are distended and their folds are smoothed out so that all parts of the surface of such channels shall be subjected to an effective action of 15 the fluid injected by the syringe.

A further object of my invention is to insure an unobstructed passage for the discharge of the injected fluid by a peculiar formation of 20 my improved attachment.

To the above ends my invention consists in the provision of a skeleton frame, of hard rubber, metal, or other suitable material, formed in two or more sections, and with peculiarly- 25 constructed extremities, as hereinafter set forth; also, in the provision of a peculiar arrangement for securing the frame to different sizes of syringe-nozzles.

In order that my invention may be fully understood, I will describe it with reference to the 30 accompanying drawings, in which—

Figure 1 is a perspective view of my improved attachment, the syringe-nozzle being removed. Fig. 2 is a longitudinal section of 35 the same, the syringe-nozzle being in position. Fig. 3 is a side view of the attachment, the nozzle being shown in dotted lines and the frame being drawn partly in section. Figs. 4 and 5 are elevations of the front and rear ends 40 of the frame, respectively.

In the said drawings, A designates the nozzle of the syringe, which may be of any preferred form, and also of any size, that shown being the form best adapted for use as a vaginal syringe.

B B designate a series of longitudinal bars forming the body of the skeleton frame, and which may be made of hard rubber, metal, or other suitable material. There may be four 50 or more of these bars B, (in the illustration six are shown,) and arranged in two sets, (in

the present illustration composed of three bars in each set,) which are connected by cross pieces or stays C D E, fastened at their respective ends to the middle bar. The bars of each are united at their forward ends by curved bars or bows F, converging inward, so as by the avoidance of any abrupt angle to facilitate the insertion of the frame into the channels to be treated. The bars of each set are connected 55 at their rear ends by segmental bars G, serving to support the said bars B, and also as the point of attachment for the lower cross-bar, E. Both the cross-bars D and E are curved or bowed coincidentally, as shown, and when the 60 nozzle A is in position rest upon the same side thereof, holding said nozzle in the longitudinal center or axis of the frame. The said nozzle is secured or locked in its place within the frame by a spring-loop, H, the two extremities of which are secured to two of the 65 bars B, as shown at h, and bearing against the side of the nozzle opposite to that in contact with the stays D and E, so as to exert a counter-pressure against said stays and keep 70 the nozzle in position. When the nozzle is not in position in the frame, the loop end of the spring H rests against the inside of the frame opposite to the points of attachment of the 75 ends of said spring. By this arrangement it 80 will be seen that the syringe-nozzle being inserted beneath the stay E, and pressed at its end between the curved end of the spring H and the inner face of the frame, it will of itself press aside the spring and enter easily into its 85 place, it being only necessary to exert the required pressure and to guide the nozzle with one hand in order to fix the nozzle in proper position. It will be seen, further, that any 90 size of nozzle can be inserted in the syringe-frame. By reference to Fig. 5, it will be seen that the construction and arrangement of the parts forming the base of the frame are such as to form a free and open passage through which the liquid discharging from the channel 95 passes without material obstruction; and, still further, by reference to Fig. 4, it will be seen that the conformation of the front end of the frame is such as to produce the very best and most thorough action of the injected liquid 100 when used in treatment of the vagina, and for this reason: the peculiar shape of the front

end of the distender or frame permits the neck of the womb to enter it, and at the same time keep the parts distended around it. The womb, being inside of the frame, receives the direct stream from the nozzle, which, being held back by the action of the spring H, nothing can come in contact with it to obstruct the stream from the syringe.

Having thus described my invention, the following is what I claim as new therein and desire to secure by Letters Patent—

1. An attachment for syringes, consisting of a skeleton frame for distending the vagina, provided with a suitable seat for the nozzle of the syringe, and a spring for clamping it thereto.

2. An attachment for syringes, consisting of a skeleton frame formed in two or more longi-

tudinal sections, and having its base end or extremity formed of a series of segmental bars 20 which are arranged in circular form and in such manner as to form an open channel for discharged fluid.

3. An attachment for syringes, consisting of a skeleton frame formed of two or more longitudinal sections, a series of cross bars or stays connecting or uniting said sections, and a suitable spring, the said stays forming bearings or seats for the syringe-nozzle, and the spring acting as a locking or securing device 30 for the nozzle.

GEORGE ABNER STILES.
